UNITED STATES PATENT OFFICE.

ELWOOD H. JARVIS, OF SAN FRANCISCO, CALIFORNIA.

LIQUID-FUEL BURNER.

1,325,095.

Specification of Letters Patent. Patented Dec. 16, 1919.

Application filed February 19, 1918, Serial No. 218,026. Renewed September 8, 1919. Serial No. 322,504.

To all whom it may concern:

Be it known that I, ELWOOD H. JARVIS, a citizen of the United States, residing at the city and county of San Francisco and 5 State of California, have invented certain new and useful Improvements in Liquid-Fuel Burners, of which the following is a specification.

The present invention relates to improvements in burners, particularly that type employed in the burning of hydrocarbon oils, particularly of heavy gravity.

The principal objects of the invention are to provide a construction having an improved burner cup, of the turbine type, rotated by fluid under pressure, one having an improved fuel supply controllable at a point within the burner cup, and one which is capable of ready swinging movement relative to the furnace opening.

To more fully comprehend the invention, reference is directed to the accompanying sheets of drawings, wherein—

Figure 1 is a plan view, partly in section, 25 of my improved construction.

Fig. 2 is a view in rear end elevation.

Fig. 3 is an enlarged detailed sectional view illustrating the mounting for the burner cup and fuel supply leading thereto.

30 In the several views of the drawings, wherein like characters of reference designate corresponding parts, 1 indicates a suitable tubular burner tip at the discharge end 2 of which the side walls taper, as at 3, 35 toward the opening 4. The opposite end of said tip is connected over one end of the opening 5 of a suitable hollow body or fitting 6, preferably of the elbow type. The other end of said opening 5 connects through

40 a pipe 7 with a suitable fitting 8, divided by the intervening wall 9 into passages 10 and 11, the passage 11 connecting with the pipe 7, as in Fig. 2 of the drawings. The inlet ends of the passages 10 and 11 connect 45 through fluid tight joints 13 and 12 with suitable connections or elbows 14 and 15, from which extend the feed pipes 16 and 17. A bracket 18, preferably of the U-shape type, secured to a support 19, preferably the 50 furnace front wall, mounts the structure through suitable studs 20 which engage the respective elbows 14 and 15, holding the same in upright position and permitting the divided fitting 8 to rotate between the same.

55 Thus it will be apparent that the burner tip is capable of an easy swinging movement

to and from the opening 21 in the furnace wall, as illustrated in dotted lines in Fig. 1 of the drawings.

Disposed concentrically within the tip 1 and body 6 and terminating short of the converging walls 3 of the tip is a fuel feed pipe 22, the rear end of which passes through the wall of the body 6 and connects through suitable pipes 23, couplings 24 and a globe valve casing 24' with the chamber 10. The pipe is formed at that portion extending rearwardly through the body 6 with a shoulder 25 which contacts with the inner surface of the rear wall of 70 the body and is retained in position thereagainst by a nut 26 passing over the projecting end thereof and engaging the outer surface of the rear wall of said body 6.

It is apparent that the fuel feed pipe may 75 be removed from within the body 6 by releasing said nut 26.

The outer end of the pipe 22 is reduced, as at 27, and mounts a pair of annular ball bearings 28 separated by a spacer 29, 80 said bearings being retained on the pipe by a nut 22'.

Secured to the outer collar of the bearings 28 is a sleeve 30 having radially disposed blades or vanes 31 arranged circumferentially thereof, with their faces at an angle to its axis of rotation and terminating short of contacting with the inner surface of the wall of the tip 1.

Threaded to the outer end of the collar 90 is one end of a suitable burner cup 32, outwardly flared toward its discharge end and projecting a slight distance beyond the end of the burner tip, as in Fig. 3 of the drawings.

95 The outer surface of the discharge end of the cup 32 is of a diameter slightly less than that of the opening 4, thereby providing an annular passage intermediate the said cup 32 and opening 4. A suitable nut 33, 100 threaded onto the pipe 22 in rear of the bearings 28, prevents rearward longitudinal movement of the bearings on said pipe, and said nut is formed with a forwardly extending flange 34 for projecting over the rear flanged edge 35 of the sleeve 30, thus providing a running fit for the rear edge of said collar. Lubricant is supplied to the bearings 28 through a pipe 35' and cup 36 connected therewith, said cup being arranged exteriorly of the body 6.

The discharge end of the pipe 22 termi-

nates adjacent the rear end of the cup 32 and the discharge of the fuel therefrom into the cup is controlled by a valve member 37 seating over the end of said pipe. The valve is capable of movement to seat over or lift from the pipe end by a controlling rod 38 of small diameter, extending longitudinally within said pipe 22 and projecting at its rear end through the casing 24 of the globe valve type and with which it has threaded connection. A handle 39 on the end of said rod permits of rotation of the same to operate said valve. The valve member 37 is preferably conical in shape with its small end or apex extending into said pipe, so that the fuel stream issuing from said pipe under slight pressure will be deflected by the walls of said valve outwardly in an even stream circumferentially thereof onto the inner wall of the burner cup.

The apparatus operates in the following manner:—The pipe 16 is connected to a source of fuel supply, under pressure, and pipe 17 is preferably connected to an air supply under pressure. However, steam may be employed if desired. The air under pressure passing through the body 5 and tip 1 strikes the blades or vanes 31 causing a rotation of the cup, the air or steam after passing from the blades or vanes follows through the tip between the outer wall of the cup and the inner wall of said tip, discharging from the tip through the space between the end of said cup and the surface of the opening 4. The unseating of the valve 37 permits the fuel under pressure to discharge circumferentially from the end of the pipe 22 onto the inner surface of the rapidly rotating cup 32, the centrifugal force of which, owing to its rotation, causes the oil to pass in a thin film longitudinally of the flaring walls thereof, and to dis-

charge radially from the end thereof in the form of small globules and at a direction substantially at right angles to the path of the stream of air or steam surrounding the cup. Thus oil is thoroughly intermixed with the steam or air on leaving the burner tip, insuring a highly combustible mixture.

By controlling the oil feed at the discharge end of the oil feed pipe, and at a point within the burner cup, the drip or any rise at the time of shutting off the oil flow, will be discharged from the cup prior to the same arriving at a point of rest, as the cup will spin or rotate after the feed of the impelling medium therefor is shut off.

Having thus described my invention, what I claim as new and desire to protect by Letters Patent is:—

A burner for liquid hydrocarbon fuels comprising a rotating burner cup, a tubular liquid fuel supply pipe extending axially through said cup and on which the same rotates, the discharge end of said pipe terminating adjacent the base of said cup, a conical valve at the discharge end of said supply pipe with the apex thereof received within the end of said pipe, said valve capable of movement to and from the discharge end of said pipe to control the discharge of fuel therefrom and to direct the fuel discharging therefrom radially of the discharge end of said pipe and against the wall of said cup, and means within said pipe and actuated from a distant point for controlling the operation of said valve.

In testimony whereof I have signed my name to this specification in the presence of a subscribing witness.

ELWOOD H. JARVIS.

Witness:

D. B. RICHARDS.
